UNITED STATES PATENT OFFICE.

FRANK W. ROSENGREN, OF CHICAGO, ILLINOIS, ASSIGNOR TO ENTERPRISE TOOL AND METAL WORKS, OF CHICAGO, ILLINOIS, A CORPORATION OF ILLINOIS.

SAD-IRON.

1,114,916.

Specification of Letters Patent.

Patented Oct. 27, 1914.

Application filed June 29, 1912. Serial No. 706,603.

To all whom it may concern:

Be it known that I, FRANK W. ROSENGREN, a resident of Chicago, in the county of Cook and State of Illinois, have invented certain 5 new and useful Improvements in Sad-Irons, of which the following is a full, clear, and exact description.

The invention relates to sad-irons.

One object of the invention is to provide 10 an improved spring-connection or cushion between the handle and the body of the iron so that the heated bottom of the iron will be yieldingly pressed into contact with the material being ironed or pressed. In practice, 15 it has been found that this yielding connection causes even pressure and is also less tiring upon the operator.

A further object of the invention is to 20 provide an improved connection between the pipe for supplying fuel to the chamber in the iron, and the body of the iron. In practice, these tubes are usually formed of thin metal, such as brass. An exceptionally heavy tube has been found to result in imperfect combustion at the outlets of the pipe 25 and therefore, it is desirable to avoid the use of a pipe having a thick surrounding wall. When a thin pipe is used and it becomes heated to a high degree, it is liable to break 30 in use, and for this reason, the invention provides improved means for securing the pipe to the body of the iron so that there will be no stresses upon the pipe while the iron is hot and in use.

Another object of the invention is to provide 35 means whereby the iron may be adapted for use in heating a vessel or article placed on the body of the iron.

The invention further designs to provide 40 a sad iron of improved construction and operation.

The invention consists in the several novel 45 features hereinafter set forth and more particularly defined by claims at the conclusion hereof.

In the drawings Figure 1 is a view, partly 50 in longitudinal section and partly in elevation, of a sad iron embodying the invention. Fig. 2 is a top plan view. Fig. 3 is a section taken on line 3—3 of Fig. 1. Fig. 4 is a detail view of the cut-off sleeve.

The body 10 of the iron has a combustion-chamber 11 therein, to which fuel is conducted by a pipe 12 which extends lengthwise 55 through the center of chamber 11. At

the outside of the body of the iron, pipe 12 is provided with a valve 13 of usual construction, for regulating the supply of gas, and a coupling or nipple 14 adapted to be connected to a flexible hose so that gas will 60 be supplied to the sad iron as it is being moved about. Within chamber 11, pipe 12 is provided, at its underside with slits 15 through which the fuel escapes from pipe 12, for ignition. As a result, combustion 65 will occur adjacent the bottom of body 10 when the bottom is to be kept hot. At one end, pipe 12 extends through the end wall 16 of body 10, and a screw 17 extends through a hole in pipe 12 to rigidly secure the pipe 70 to one end of body 12. The other end of pipe 12 fits into a seat 18 formed in a lug 19 at one end of body 10 and a screw 20 extends through the pipe and through a plug 21 fitted into the end of the pipe, and into the 75 bottom of lug 19. As a result of rigidly securing both ends of pipe 12 in the body of the sad-iron, there will be no stresses or strains applied to the burner portion, or that portion of the pipe in the body 10 which becomes 80 hot in use and therefore all danger of breaking the pipe is avoided. Pipe 12, outside of the iron does not become so hot as to warrant danger of breakage. Holes 22 are formed in sides of body 10 adjacent the bottom 10^a to supply air for combustion to chamber 11. Ribs 23 are formed on bottom of bottom 10^a between the holes 22. Side walls 10^b are formed with openings 24 for admitting air adjacent the cover 25 which 85 extends over the combustion chamber 11 and said cover is removably connected to body 10 by a headed screw 26 which is adapted to hold the slotted front end of cover 25 and a latch 27 which is pivoted to a screw 28 which 90 is secured in the body. This latch may be turned into position indicated in dotted lines Fig. 2, so that it will be disposed over the slot 29 in cover 25 to permit the cover to be removed.

A handle 30 is secured to a loop 31 which is formed of a strip of metal, to elevate the grip-portion of the handle above the top of the sad iron. Loop 31 is secured, by screws 32, to the upper member of a resilient 105 U-shaped strip 33 which has its lower member secured by screws 34 to the cover 25, and a strip of asbestos or heat insulating material 34^a is interposed between the strip and the cover, so that the heat from the com- 110

bustion chamber will not be readily transmitted to the handle. This strip 33 is formed of a heavy strip of metal and a stop-screw 36 is secured in the upper member of strip 33, extends through the other member of the strip, the insulating strip 34^a and cover 25, and has a head 37 which limits the upward movement of the upper arm of strip 33. Screw 36 also prevents lateral movement of the handle relatively to the top of the sad iron. The resilient strip and stop thus provide a yielding or resilient connection between the handle and the iron which serves as a cushion whereby even pressure will result, and the pressing operation will be rendered more easy for the operator. It will be observed that this yielding connection is so constructed that the iron can be manipulated laterally or forwardly and backwardly the same as if a rigid connection were applied. In other words, the yielding connection is such, that the iron may be positively operated in any direction but permits yielding only in that direction in which pressure is exerted to force the iron into contact with the material being pressed or ironed.

The device is adapted to be used as a sad-iron and also as a heater for a vessel or article placed upon the body. For this purpose, burner-pipe 12 is provided, in addition to the series of slits 15 which direct the fuel downwardly, with a series of slits or openings 15^a which are disposed to direct the fuel upwardly. A cut-off sleeve or valve 40 is rotatably held on pipe 12 and extends between a wall 16 and lug 19 so that it will be held against longitudinal movement on the pipe 12. This sleeve is partly cut away and can be turned to bring the cut-away into position to permit the fuel to escape downwardly through slits 15 and close slits 15^a or into position to close slits 15 and permit the escape of fuel through the slits 15^a. A stop-pin 41 limits the movement of the sleeve between its alternative positions. A stud 42 is fixed to one end of sleeve 40 so that it can be readily turned. As a result of this construction, the device may be used as a sad-iron and by removing cover 25 and the handle secured thereto, and rotating sleeve 40 to cut off the escape of fuel through slits 15 and to open the slits 15^a, the flame will be

directed upwardly to heat a vessel or other article which may be placed upon body 10. 55 In this manner, the improved device may be used for a number of different purposes.

The invention is not to be understood as restricted to the details set forth, since these may be modified within the scope of the appended claims without departing from the spirit and scope of the invention. 60

Having thus described the invention, what I claim as new and desire to secure by Letters Patent, is:

1. A sad-iron comprising a body, a cover, a handle, and a resilient strip one part of which is secured to the handle and the other part to the cover, forming a yielding connection between the handle and the iron. 70

2. A sad-iron comprising a body, a cover, a handle and a U-shaped resilient strip having a member secured to the handle, a parallel member secured to the cover, forming a yielding connection between the handle and the iron. 75

3. A sad-iron comprising a body, a cover, a handle, and a resilient strip secured to the handle and to the cover, forming a yielding connection between the handle and the iron, 80 and a stop for limiting the vertical movement of the handle relatively to the cover.

4. A sad-iron comprising a body, a cover, a handle, a U-shaped strip secured to the handle and to the cover, forming a yielding 85 connection between the handle and the iron, and a stop-screw on one member of said strip and extending through the other member and the cover to limit the movement of one member relatively to the other. 90

5. A sad iron comprising a body, a handle, and resilient means secured to the handle and to the body, forming a yielding connection between the handle and the body to permit the iron to be yieldingly pressed into 95 contact with the material being ironed or pressed.

6. A sad iron comprising a body and a handle, and cushioning means between said body and handle to permit the iron to be 100 yieldingly pressed into contact with the material being ironed or pressed.
